ATTORNEYS

UNITED STATES PATENT OFFICE.

LAMBERT F. FOUTS, OF TRINITY MILLS, TEXAS.

ANNUNCIATOR.

SPECIFICATION forming part of Letters Patent No. 461,748, dated October 20, 1891.

Application filed June 5, 1891. Serial No. 395,171. (No model.)

To all whom it may concern:

Be it known that I, LAMBERT F. FOUTS, of Trinity Mills, in the county of Dallas and State of Texas, have invented a new and Improved 5 Annunciator, of which the following is a specification, reference being had to the annexed drawings, forming a part thereof, in which—

Figure 1 is a side elevation of my improved circuit-closer, showing the circuit diagrammatically. Fig. 2 is a front elevation, and Fig. 3 is a vertical transverse section taken on line *x x* in Fig. 2.

Similar letters of reference indicate corresponding parts in all the views.

15 The object of my invention is to provide a circuit-closing attachment for annunciators by means of which an electric lamp will be lit when the annunciator-drop falls.

My invention consists in the construction 20 and arrangement of parts hereinafter described and claimed.

In the annunciator A is the electro-magnet *a*, mounted on the base-plate *B*, and in a standard *b*, projecting from the base-plate, is fulcrumed the armature-lever *C*, which extends 25 in one direction over the magnet *a* and in the opposite direction through a mortise in the annunciator-drop *D*. The drop *D* is pivoted in an extension of the base-plate and is inclined slightly when in its position of rest, so 30 that it will fall by gravity when released from the catch *c* on the end of the armature-lever *C*. The armature-lever is held normally out of contact with the electro-magnet by a retractile spring *d*, connected with a prolongation 35 of the armature-lever and with a stud projecting from the standard *b*. In an arm *e*, projecting at right angles from the standard *b*, is inserted a screw *f*, which limits the 40 downward movement of the catch end *c* of the armature-lever *C*.

The base-plate *B* is mounted upon a block 45 *E*, in the front end of which are secured the wires *g h*. To the wire *h* is attached a contact-spring *i*, which is held normally out of

contact with the wire *g*. The said contact-spring *i* is supported within the path of the drop *D*, so that when the said drop is released from the catch *c* it will strike the spring *i* and close the circuit between the wires *g h*. The 50 wires *g h* are connected up in the circuit of the battery *F*, as shown, an electric lamp *j* and switch *k* being inserted in the circuit.

The annunciator A is designed to be used in a burglar-alarm system, the circuit-closing 55 devices and battery being connected with the terminal wires of the magnet *a* in the usual way. When a sufficient amount of current of electricity is thrown upon the magnet *a* by the opening of a window or door, the armature-lever *C* is tilted and the annunciator-drop *D* falls, striking the contact-spring *i* and closing the circuit of the battery *F*, thus causing the lamp *j* to become luminous. After 60 the trouble is located the lamp *j* is extinguished by opening the switch *k*.

Although I have described my invention in connection with a burglar-alarm, I do not limit or confine myself to this use of the apparatus, as it may be applied to danger-signals and other signals with equal advantage. 70

Having thus described my invention, I claim as new and desire to secure by Letters Patent—

The combination, with the annunciator A, 75 mounted on the block *E* and provided with the drop *D*, of the wires *g h*, secured one above the other to the block below the lower hinged end of the drop, the spring *i*, secured at its lower end to the lower wire *h* and extending at its upper end across but out of contact with the wire *g* and in the downward path of the drop to be thrown thereby against the wire *g*, a battery-circuit connected with said wires, and a signal in said circuit, substantially as set forth. 80

LAMBERT F. FOUTS.
